UNITED STATES PATENT OFFICE.

JOHN C. WAHL, OF CHICAGO, ILLINOIS, ASSIGNOR, BY MESNE ASSIGNMENTS, TO THE WAHL COMPANY, OF WILMINGTON, DELAWARE, A CORPORATION OF DELAWARE.

CALCULATING-MACHINE.

1,314,105.

Specification of Letters Patent. Patented Aug. 26, 1919.

Application filed September 20, 1911. Serial No. 650,350.

To all whom it may concern:

Be it known that I, JOHN C. WAHL, a citizen of the United States, residing at Chicago, in the county of Cook and State of Illinois, have invented certain new and useful Improvements in Calculating-Machines, of which the following is a specification.

My invention relates to calculating machines, such as the calculators attached to typewriters, and more particularly to the reversing of the calculator from addition to subtraction and an accompanying shifting of the typewriter polychrome ribbon so that the ribbon will print the subtracted numbers in a different color from the added ones. The calculator illustrated here is the Wahl adding machine now on the market and described in quite a number of issued patents among them No. 893,719, issued to me July 21, 1908. The typewriter chosen for illustration is the new Remington, model #10.

The specification is accompanied by the drawings of which:

Figure 1 represents a front elevation of the typewriter and calculator just mentioned.

Fig. 2 is an enlarged view of the connection between the calculator and the ribbon shifting parts, already shown to a smaller scale in the left portion of Fig. 1.

Figs. 3 and 4 show elevations from the left side of the parts on the calculator immediately concerned with the shifting of the ribbon. Fig. 3 shows the parts in adding position and Fig. 4 shows them in subtracting position.

Fig. 5 shows a plan view of a detail of the reversing cam.

Fig. 6 shows a detached plan view of the parts on the ribbon shifting shaft taken partly in section along the plane 6—6 of Fig. 7.

Fig. 7 shows a front elevation of the same.

Fig. 8 shows a section of the same taken along the plane 8—8 of Fig. 7.

Fig. 9 is a perspective view of the pointer spring piece.

The typewriter is the ordinary Remington typewriter now on the market. To illustrate it, there are represented its framework 1, the letter keys 2, the numeral keys 3. Of course there are supposed to be present key levers, links, typebars, escapement, carriage, and the other mechanisms which are to be found upon a typewriter, and which enter

into its construction. But as they do not form a part of the invention, and the bringing of them into the explanation or the drawings would tend to confuse rather than to clarify, they will not be referred to in greater detail.

To represent the calculating machine, there is present a master mechanism, under the cover 4. The master mechanism includes the master wheel 7. There are also present the totalizer 5 and the carriage bar 6. As usual the totalizer contains carrying wheels 8 which coöperate with the master wheel and pass over and mesh with it during the operation of the machine. The exact construction and operation are thoroughly described in the above cited Patent, No. 893,719, to which reference is made for a detailed description of the parts.

As also described in said patent, the calculating machine is provided with a reversing shaft 10, this is the mechanical equivalent of rod 54, Fig. 5, of the above-mentioned patent. This is capable of being manually moved into either of two positions. When it is in one position, it is so connected with the master wheel 7 that its rotation will produce addition. When the shaft is in its other position, the master wheel will rotate in the opposite direction and will thus produce subtraction. Mounted upon the left part of the calculator is the plate 11 forming a portion of the framework of the machine. Forming a part of said plate is an ear 12 which serves as a bearing for the left end 13 of the reversing shaft 10. Fastened in 13 is a pin 14 which is firmly secured therein by a set screw 15. Pivotedly mounted upon a screw 20 fastened into plate 11 is the reversing handle 21 which has formed thereon at its front portion the reversing finger piece 22. Rigidly fastened to the reversing handle is the reversing cam 23 which has extending therefrom an arm 24 fastened to one end of an extension spring 25 whose other end is fastened to a stud 26 riveted into the plate 11. The reversing finger piece is thus given a constant tendency upward and will rise if pushed down. The reversing cam 23 has also formed therein a circular groove 27 through which there enters into the plate 21 a screw 28. The ends 29 and 30 of the circular groove limit the motion of the reversing handle.

Formed on the upper part of the reversing

cam, is a cylindrical extension 31 into which is cut a helical cam slot. This cam slot is composed of a portion 33 which lies in a plane perpendicular to the axis of the cylinder, a portion 34 which lies in a plane inclined to the axis of the cylinder, and another portion 35 which again is perpendicular to the axis of the cylinder. The slots 33, 34, and 35 coöperate with the pin 14 in the reversing shaft 10. It is therefore evident that the depressing of the finger piece 22 will cause a lengthwise motion of the reversing shaft 10 in its bearings and the consequent change of the machine from its adding to its subtracting condition.

Normally the reversing handle is in its up position, and the calculator is in its adding condition. The two slot portions 33 and 35 perpendicular to the axis of the cylindrical cam are intentionally made longer than is necessary to coöperate with the reversing shaft. The pin 14 will therefore not contact with the ends of these slots and there will thus be no strain on said pin due to the manual operation of the reversing handle. The strain of spring 25 on one side or of the finger on the other side is all taken by the screw 28.

In the operation of the machine, when the operator desires to subtract, he depresses the finger piece 22 and keeps it depressed while he operates the figure keys of the machine. Upon his releasing of the reversing handle, the spring immediately brings the reversing handle back to its normal position and the machine thus automatically returns to its adding condition.

For the correction of errors such as the insertion of a wrong number or digit into the machine, the spring return of the reversing lever is of marked advantage over the structure disclosed in my patent above referred to. In the present structure when a wrong number is inserted in the calculating machine (assuming the machine to be in the adding position at that time) the finger piece 22 is depressed and held depressed while the wrong number is again inserted. Since the first insertion was positive and the latter negative, the two cancel one another and the erroneous number is thereby withdrawn from the machine. The finger piece 22 is then allowed to come to its normal or adding position, thus bringing the machine to its original condition and the correct number inserted. It is obvious that the above recited method of correcting errors is much less liable to mistake than the method required with the machine described in my above-mentioned patent, for in the latter case it is necessary for the operator, after having put the machine in a subtracting condition and inserted the error a second time, to restore the machine to an adding condition before inserting the correct num-

ber. In case this restoring is overlooked, there results a second error. With the device shown in my present application, it is necessary to hold the machine in the subtracting condition, while the error is being corrected, and as soon as pressure is withdrawn from the finger piece 22 the spring 25 automatically returns the machine to its proper condition.

Sometimes it is necessary to subtract more than one number at a time, and the necessity of keeping the reversing handle continuously depressed during the said subtraction of numbers becomes quite an annoyance. The machine has therefore been provided with a retaining handle 40 which is pivotally mounted upon a screw 41 fastened into the plate 11. The retaining handle is provided with a retaining finger piece 42 and a hook 43 which coöperates with an extension 44 on the reversing handle. The extension 44 is formed with a circular edge 45 and a radial edge 46. Normally the parts are in the position shown in Fig. 3 and it is evident that the depressing of the reversing handle will leave it unaffected by the retaining piece. But whenever the operator grasps not only the reversing handle, but the retaining handle as well, then he brings them into the position shown in Fig. 4 where the hook 43 of the retaining handle is caught over the radial edge 46 of the reversing handle. As the operator now releases both handles, the tension of spring 25 keeps them in their caught position, and the reversing handle therefore remains in the subtracting position. To release the same from the retaining handle, it is sufficient to slightly depress the finger piece 22, whereupon the force of the spring 25 is removed from the hook 43. Thereupon said retaining handle moves down under gravity a sufficient distance to release the reversing handle. As soon as the operator removes his finger from the latter, it rises under the influence of its spring 25 and resumes its normal position for adding.

The circular edge 45 of the extension 44 upon the reversing handle is for the purpose of preventing the retaining hook 43 from locking the reversing handle until the latter is in its fully depressed position.

Mounted in the framework of the typewriter is the ribbon shifting shaft 50 which operates in the same manner as the one upon the Remington #10 machine now on the market. That is, its rotation about its axis shifts the polychrome ribbon so that another portion thereof is struck by the type. The shaft is supported at its front end by an indicator plate 51 which is fastened by two pins 52 to the framework of the typewriter. Rotating with the shaft is a pointer 53 which may thus be brought into either of two locations indicated by the radial sector 130

marked R and B (for red and black) in Fig. 7. This pointer 53 is in front of the indicator plate 51. Rigidly fastened to the shaft 50 at the back of said plate is a spring piece 54 provided at its end with a small stud 55 which is adapted to enter into either of two holes 56 or 57 of the indicator plate 51. The entering of the stud 55 into either of these holes tends to keep the shaft in its placed position and this tends to retain the ribbon also in its corresponding position. The shaft 50 may, however, be forcibly twisted to withdraw the stud 55 from the hole in which it has entered, whereupon it may be brought to enter the other hole. Thus far the mechanism is absolutely similar to that found upon the ordinary Remington machine. As remarked above, however, it has been found advisable to combine the retaining handle mechanism of the calculator with the ribbon shifting mechanism of the typewriter. This is accomplished as follows: Pivottally mounted upon a screw 60 fastened into the plate 11 of the calculator is a bell crank lever 61 which has a short arm 62 in which there is riveted a stud 63 which enters into a slot 64 cut into an arm 65 forming a part of the retaining handle 40. Extending from the bell crank lever 61 is another arm 66 which is fastened to one end of a link 67 whose other end is fastened to an arm 68 rotatably mounted upon the ribbon shifting shaft 50. The operating of the retaining handle will therefore also rotate the arm 68 about said shaft.

The spring piece 54 rigidly fastened to the shaft 50 is formed with two extensions 70 and 71. Rigidly fastened to the shaft immediately behind the spring piece 54 is a collar 72 formed with two bevels 73 and 74. Slidably mounted upon the front portion of the shaft 50 is a knurled head 75 to which is rigidly fastened a spring pointer 76 which has thereon a pointer 77 to indicate in what position the knurled head is placed, a slot 78 and a spring extension 79 whose end is formed into a bevel piece 80. The bevel 80 co-operates with the two bevels 73 and 74 of collar 72 and the spring extension 79 enters between the two extensions 70 and 71 which are rigidly fastened to the shaft 50. It is therefore evident that the knurled head 75 may be pulled forward or pushed back upon the shaft 50 and that bevel piece 80 will keep it in either of its located positions. Moreover the knurled head may be rotated about its axis and this rotation by means of spring 79 and the extensions 70 and 71 will be imparted to the shaft 50.

The slot 78 co-operates with a pin 81 fastened in the arm 68 but the pin 81 is short and therefore enters the slot 78 only when the knurled head is in its back position and does not enter the slot when the head is in its front position. It will thus be seen that

when the knurled head is in its back position and the retaining lever be raised that the ribbon shifting shaft will be rotated and the ribbon itself shifted. But that when the knurled head 75 is in its front position any movement of the retaining lever will not affect the shaft 50 or the ribbon, but that any rotation of the knurled head 75 will rotate the shaft and shift the ribbon. The mechanism may therefore be so set that the retaining handle and ribbon will operate together and any operation of the retaining lever will cause the printing in a different color, and it may be so set that the calculator and ribbon mechanism will be disconnected from each other and neither affect the other. Again, when so disconnected the polychrome ribbon may be shifted without interference by hand. Moreover, even when the calculator and ribbon mechanism are connected, the operator still has a choice of reversing the calculator and simultaneously shifting the ribbon, or reversing the calculator without simultaneously shifting the ribbon.

As it requires some slight degree of force to overcome the tendency of the ribbon to remain in either of its placed positions, there has been added a pin 90 fastened in the reversing handle and an arm 91 to co-operate therewith extends from the retaining lever. When the reversing lever is released by the depression of its finger piece 22 and the retaining handle and hook have dropped down under gravity sufficiently to release the radial edge 46, (the parts have sufficient lost motion for that purpose) the reversing handle under the influence of its spring 25 brings the pin 90 into contact with the arm 91 on the retaining lever. Thereupon, the further returning motion of the reversing handle forces the retaining handle back to its normal or lower position and thus simultaneously shifts the ribbon back to its normal position. It is thus seen that it is not necessary to go through a special manipulation to return the ribbon to its normal position, as the mere release of the reversing handle suffices for the purpose.

It can be seen that the depressing of the reversing finger piece 22 produces no effect upon the ribbon mechanism but that the raising of the retaining finger piece 42 not only shifts the ribbon but also, because of the arm 91 and the stud 90, operates upon the reversing cam and changes the condition of the machine from adding to subtracting. A slight further depression of the reversing finger piece 22 will then result in the locking of the reversing cam and the retaining lever. By this mechanism, it is therefore possible to operate both the reversing lever and the ribbon mechanism simultaneously.

Having thus described my mechanism, I claim:

1. In a calculating machine, the combination

- tion of a reversing device adapted to place the machine in either adding or subtracting condition; mechanism tending to return the machine to adding condition if displaced 5 therefrom; mechanism to operate the machine; and manually operable detent means to retain the reversing mechanism in its displaced condition, and thus keep the machine in subtracting condition if so desired, said detent means being adapted to be manually operated independent of the action of any other part of said machine.
2. In a calculating machine, the combination of a reversing device adapted to throw the machine into either an adding or subtracting condition; a key lever which when up retains the machine in adding condition, and which when down, retains the machine in subtracting condition, and whose movement changes the machine from one condition to another; means constantly tending to bring the key into its up position and manually operable detent means to retain the key lever in its down position to thus 20 keep the machine in subtracting condition, substantially as described, said detent means being adapted to be operated independent of the operation of any other part of said machine.
3. In a calculating machine, capable of being put in adding or subtracting condition; manually operable reversing mechanism to change the machine from adding to subtracting condition; a spring to operate 25 with said mechanism and constantly tending to place the machine in adding condition; a detent operative upon said mechanism to detain it in completely subtracting position against the force of the spring 30 whereby the mechanism is either in completely subtracting condition or automatically returns to completely adding condition, said detent being adapted to be manually operated independent of the action of 40 any other part of the machine.
4. In a combined typewriting and computing machine, the combination of a reversing device to set said machine in subtracting condition; a spring device tending 45 to restore said reversing device to an addition condition; a detent to hold said reversing device in the subtracting condition against the operation of said spring device; a ribbon shift device adapted to be operated simultaneously with said reversing device; and connections between the said detent, reversing device, and ribbon shift whereby the restoration of said ribbon shift occurs simultaneous with the restoration of the reversing device to an addition condition on the release of said detent.
5. In a combined typewriting and computing machine, the combination of a gear reversing device to set said machine in subtracting condition; a spring device tending 50 to restore said gear reversing device to an addition condition; a detent to hold said gear reversing device in the subtracting condition against the operation of said spring device; a bi-chrome ribbon shift device adapted to be operated simultaneously with said gear reversing device; and connections between the said detent, gear reversing device and bi-chrome ribbon shift whereby the restoration of said bi-chrome ribbon shift occurs simultaneous with the restoration of the gear reversing device to an addition condition on the release of said detent.
6. In a combined typewriting and computing machine, the combination of a gear reversing device to put the machine in a subtracting condition, a spring device tending to restore said gear reversing device to an addition condition; a detent to hold said gear reversing device in the subtracting condition against the operation of said spring device, a ribbon shift device to be operated simultaneously with said gear reversing device, said ribbon shift device being adapted to shift a ribbon containing 70 two colors, and being so arranged that numbers entered into the machine in addition are printed in black and numbers entered into the machine in subtraction are printed in red; and connections between said detent 75 and gear reversing device and ribbon shift whereby the restoration of said ribbon shift occurs simultaneously with the restoration of said gear reversing device to an addition condition on the release of said detent.
7. In a calculating machine, capable of being put in adding or subtracting condition: means to change it from one condition to the other; a manually reciprocatable helical cam to operate said means, said helical cam locking said means in adding condition at one end of its reciprocation, and in subtracting condition at the other end of its reciprocation.
8. In a calculating machine, capable of being put in adding or subtracting condition: means to change it from one condition to the other; a manually reciprocatable helical cam and pin to operate said means, said cam locking said means in adding condition at one end of its reciprocation, and in subtracting condition at the other end of its reciprocation.
9. In a calculating machine, capable of being put in adding or subtracting condition: means to change it from one condition to the other; a manually reciprocatable helical slotted cam and pin to operate said means, said cam locking said means in adding condition at one end of its reciprocation, 100 and in subtracting condition at the other end of its reciprocation.
10. In a calculating machine: a master wheel capable of being put in adding or subtracting condition; mechanism tending 105
- 110
- 115
- 120
- 125
- 130

to return the master wheel to adding condition if displaced therefrom; and mechanism to operate the master wheel.

11. In a calculating machine: a master wheel capable of being put in adding or subtracting condition; a key lever movable to either of two positions to thereby change the master wheel from one to the other condition; means constantly tending to return the key to a given one of the two positions to thereby normally place the master wheel in adding condition, substantially as described.

12. In a calculating machine: a master wheel capable of being put in adding or subtracting condition; a key lever which when up retains the master wheel in adding condition, and which when down retains the master wheel in subtracting condition and whose movement changes the master wheel from one condition to the other; and means constantly tending to bring the key to its up position, substantially as described.

13. In a calculating machine: a master wheel capable of being put in adding or subtracting condition; mechanism tending to return the master wheel to adding condition if displaced therefrom; mechanism to operate the master wheel; and manually operable detent means to retain the returning mechanism in displaced condition, and thus keep the master wheel in subtracting condition if so desired.

14. In a calculating machine: a master wheel capable of being put in adding or subtracting condition; a key lever which when up retains the master wheel in adding condition and which when down retains it in subtracting condition, and whose movement changes the master wheel from one condition to the other; means constantly tending to bring the key into its up position; and manually operable detent means to retain the key lever in its down position to thus keep the master wheel in subtracting condition, substantially as described.

15. In a calculating machine: a master wheel capable of being put in adding or subtracting condition; manually operable mechanism to change the master wheel from adding to subtracting condition; a spring co-operating with said mechanism and constantly tending to place the master wheel in adding condition; a detent operative upon said mechanism to detain it in completely subtracting position against the force of the spring, whereby the mechanism is either in completely subtracting condition or automatically returns to completely adding condition.

16. In a calculating machine: a master wheel capable of being put in adding or subtracting condition; means to change it from one condition to the other; a manually

reciprocatable helical cam to operate said means, said helical cam locking said means in adding condition at one end of its reciprocation, and in subtracting condition at the other end of its reciprocation.

17. In a calculating machine: a master wheel capable of being put in adding or subtracting condition; means to change the master wheel from one condition to the other; a manually reciprocatable helical cam and pin to operate said means, said cam locking said means in adding condition at one end of its reciprocation, and in subtracting condition at the other end of its reciprocation.

18. In a calculating machine: a master wheel capable of being put in adding or subtracting condition; means to change the master wheel from one condition to the other; a manually reciprocatable helical slotted cam and pin to operate said means, said cam locking said means in adding condition at one end of its reciprocation and in subtracting condition at the other end of its reciprocation.

19. In a recording calculating machine: ribbon shifting means to change the color of the printing; reversing mechanism to change the machine from adding to subtracting condition; retaining means to retain the reversing mechanism in its subtracting condition when placed therein; the retaining means and ribbon shifting means co-operating so that a change in one produces a change in the other.

20. In a calculating recording machine whose calculating portion is adapted to be changed from adding to subtracting condition, and whose recording portion is adapted to be changed in condition so as to print in another color; mechanism operating upon both the calculating portion and the recording portion to change the condition of both simultaneously; and disconnecting mechanism to establish a disconnection between the calculating portion and the recording portion whereby the calculating portion may be changed without changing the recording portion.

21. In a recording calculating machine, the combination of means to change the machine from an adding to a subtracting position, a record changing means adapted to change the machine to print in a different color, said record changing means and calculation changing means being normally connected, and means to render the calculating changing means inoperative upon the record changing means whereby the calculating means may be changed from addition to subtraction without affecting the recording means.

22. In a recording calculating machine, the combination of calculating changing means adapted to change the machine from

- an adding to a subtracting condition, a record changing means adapted to change the machine to print in different colors, said record changing and calculating changing means 5 being normally connected, whereby the operation of one operates the other, and means adapted to disconnect the record changing means from the calculating changing means, whereby the record changing means may be 10 changed so as to determine that the machine shall print in a different color without changing the calculating changing means.
23. In an adding and subtracting typewriter printing in two colors: a color shaft 15 to change the color of the printing; a retaining reversing lever to change the typewriter from adding to subtracting condition; a link uniting the color shaft with the retaining reversing lever so that a movement 20 in one causes a movement in the other for the purpose described; and manually operable means for disconnecting the retaining reversing lever from the color shaft whereby the retaining reversing lever will be moved 25 without moving the color shaft.
24. In a recording calculating machine: ribbon shifting means to change the color of the printing; reversing mechanism to change the machine from adding to subtracting condition; retaining means to retain the reversing mechanism in its subtracting condition when placed therein, the retaining means and ribbon shifting means 30 cooperating so that a change in one produces a change in the other; and manually operable disconnecting means to disconnect the ribbon shifting means from the retaining means whereby a change in the ribbon shifting means will not produce a change in the 35 retaining mechanism.
25. In a recording calculating machine: ribbon shifting mechanism to change the color of the printing; reversing mechanism to change the machine from adding to subtracting condition; retaining mechanism to retain the reversing mechanism in its subtracting condition when placed therein, the retaining mechanism and ribbon shifting mechanism 40 cooperating so that a change in one produces a change in the other; and manually settable disconnecting means to disconnect the ribbon shifting mechanism from the retaining mechanism whereby a change in the retaining mechanism will not produce a change in the ribbon shifting mechanism.
26. In a recording calculating machine: ribbon shifting mechanism to change the color of the printing; reversing mechanism 45 to change the machine from adding to subtracting condition; retaining mechanism to retain the reversing mechanism in its subtracting condition when placed therein, the retaining mechanism and ribbon shifting mechanism 50 cooperating so that a change in one produces a change in the other; and manually settable disconnecting means to disconnect the ribbon shifting mechanism from the retaining mechanism whereby a change in the retaining mechanism will not produce a change in the ribbon shifting mechanism.
27. In a recording calculating machine: ribbon shifting mechanism to change the color of printing; reversing mechanism to change the machine from adding to subtracting condition; connecting means capable of being manually located in either of two positions in one of which it connects the reversing mechanism and the ribbon shifting mechanism so that a change in one produces a change in the other, and in the other of which positions it disconnects the two, so that either may be changed without affecting the other. 85
28. In a recording calculating machine: ribbon shifting mechanism to change the color of the printing; a reversing mechanism to change the machine from adding to subtracting condition; retaining mechanism to retain the reversing mechanism in its subtracting condition when displaced therein; and connecting means capable of being manually located in either of two positions in one of which it connects the retaining mechanism and the ribbon shifting mechanism so that a change in one produces a change in the other, and in the other of which positions it disconnects the retaining mechanism and the ribbon shifting mechanism, so that either may be changed without affecting the other. 90
29. In an adding and subtracting typewriter: a reversing lever to change the typewriter from adding to subtracting condition; a retaining lever to keep the reversing lever in its subtracting position when placed therein; a ribbon shifting shaft to change the color of the printing; a knob on said shaft capable of being manually located in either of two positions, in one of which it connects the ribbon shifting shaft and the retaining lever whereby the movement of either produces a corresponding movement in the other, and in the other of which positions it disconnects the two whereby the movement of either does not affect the other. 105
- In witness whereof, I have hereunto subscribed my name in the presence of two witnesses.
